UNITED STATES PATENT OFFICE.

PERCY MATHER, OF LONDON, ENGLAND.

HEAT-EXCHANGING APPARATUS.

Application filed January 4, 1922. Serial No. 527,024.

To all whom it may concern:

Be it known that I, PERCY MATHER, a subject of the King of Great Britain and Ireland, residing at 23 Great Winchester Street, London, E. C., England, have invented certain new and useful Heat-Exchanging Apparatus, of which the following is a specification.

This invention relates to pre-heaters, heat exchangers, condensers and the like and has among its objects to provide an apparatus of standard units and of a convenient construction adapted for the effective utilization of the residual heat of fluids, such as the hot residue of the distillation of crude mineral oil and the hot vapours evolved in its fractional distillation.

The apparatus of the invention is especially conceived in relation to the method which is the subject matter of a co-pending application Serial No. 526,900 dated January 4, 1922 according to which crude oil before admission for fractional distillation in the still is pre-heated, and the heat of the hot still vapours and of the hot liquid residue of distillation is used for this purpose, under conditions in which there is an effective exchange of heat and in which light fractions are recovered from the crude oil, and condensates recovered from the still vapours.

According to the invention the pre-heaters, heat exchangers, condensers or the like (hereinafter referred to as heat exchangers) are provided with nests of evaporator tubes comprising vertical series of evaporator tube sets that are horizontally disposed and so connected to vertical columns or headers that the heat yielding fluids may circulate through the tube sets as in a coil.

The invention comprises the constructional features which are hereinafter described.

The invention is illustrated in the accompanying drawings in which—

Figure 1 represents an elevation of a heat exchanger constructed according to the invention, the casing being shown in section.

Figure 2 is a sectional plan view on the line 2—2 of Figure 3.

Figure 3 is a section on the line 3—3 of Figure 2.

Figure 4 is a section on the line 4—4 of

Figure 6 through one of the headers on the right hand side of Figures 1 and 2.

Figure 5 is a detail side elevation on a larger scale showing one of the headers on the left hand side of Figures 1 and 2, while Figure 6 is a similar detail side elevation showing one of the headers on the right hand side thereof.

In carrying the invention into effect according to the illustrated construction, four units or nests 1, 2, 3, 4, of evaporator tubes are constructed as hereinbefore described, and are disposed in a casing *a*. These nests are provided for carrying out the method of pre-heating crude mineral oil or other liquids as described in the specification of the co-pending application first mentioned, and for this purpose the two lower nests 3 and 4 are provided for the circulation of hot vapour, while the two upper nests 1 and 2 are provided for the circulation of the hot residue from the still. Each of the nests 1, 2, 3, 4 is constructed of two vertical series of evaporator tube sets of the form described in the specification of the further co-pending application referred to, each tube set comprising, in the illustrated construction, four longitudinal tubes *b* connected to, and communicating at their respective ends with a transversely disposed tube *c* of larger diameter than the longitudinal tubes. One end of each of the transverse tubes *c* is closed, while the other, which is open, is flared outwardly and is adapted for the retention of a loose connecting flange *c'*, by means of which the respective transverse tubes may be connected by four bolts, on one of the parallel disposed lateral faces of the headers *d*, *d'*, *d''*, *d'''*, whereby the respective tube sets *b*, *c* are carried in a horizontal position by and between the headers *d* and *d'* or *d''* and *d'''*.

The headers *d*, *d'*, *d''*, *d'''*, and the evaporator tube sets *b*, *c* are carried within frames each comprising vertical frame members *e* of angle section, horizontal and longitudinal members *f*, and sets of transverse frame members *f'* at the lower part of the frame, which are adapted for the reception of the bases of the respective headers. Two separate carrying frames are provided for the nests 1 and 3, and 2 and 4 respectively. The

frame members f^1 are supported at their respective ends by sets of wheels e^1 , mounted to run on rails g laid in the bottom of the casing. One side a^1 of the casing is adapted 5 to be removed for the purpose of withdrawal of the respective nests of tubes, after the pipe connections have been unfastened.

Sets of diagonal braces r advantageously formed of bars of an angular cross section 10 are provided between the respective headers d , d^1 and d^2 , d^3 to ensure rigidity of construction; and the outer ends of certain of the transverse tubes c are secured to the frame by means of metal loops s connected 15 to the frame members by means of nuts.

It will be understood that the evaporator tubes b , c are horizontally disposed and that the longitudinal tubes b of the respective sets are parallel and the corresponding tubes 20 of the respective sets are disposed in vertical line. Thus the respective pairs of vertically disposed columns or headers d , d^1 and d^2 , d^3 support between them two vertical series of tube sets b , c , the respective 25 series being connected to the columns or headers on opposite and parallel disposed faces.

With a view to economize space and to ensure compactness, the alternate sets of 30 evaporator tubes b , c in each one of the vertical series of such sets are so positioned that their respective transversely disposed tubes c , at each end of the tube sets, form two separate vertical series at such a distance apart that the respective transversely disposed tubes c of each vertical series of such tubes on the same side of the column or header, may be brought a slight distance one above the other, so that 40 thus the adjacent tube sets b , c are closely disposed together, whereby a considerable area of evaporating surface is presented within a relatively small space. It will be understood that by such an arrangement the 45 transversely disposed tube c at one end of each set of tubes is positioned in the outermost vertical series of transverse tubes at one side of the casing and the tube c at the other end of each set of tubes in the innermost series at the opposite side, so that thus 50 all the longitudinal tubes and tube sets may be provided of the same standard length. By such means identical nests or units are provided, each comprising two vertical columns or headers disposed at opposite sides of the casing for the support between them of two vertical series of evaporator tube sets b , c which form a circuit for the hot fluid in the manner before described.

60 The vertically disposed columns or headers d , d^1 , d^2 and d^3 are closed at their respective upper and lower ends. The headers may be provided common to the superposed nests of tubes or those for each nest 65 may be separately provided. In the illus-

trated construction, at one side of the heat exchanger one common header d or d^2 is advantageously provided for the nests 1 and 3, or 2 and 4, and in the headers d and d^2 transverse partitions h are provided to form 70 a vertical series of inclined passages or compartments for the passage of the hot fluid, such as the hot still vapours or the hot liquid residue, from one set of longitudinal tubes in one plane upon one side of the nest, to 75 the next in the series in another or higher plane, on the other side of the nest, the arrangement being such that on the hot fluid passing in separate streams through the longitudinal tubes b of one tube set, it then 80 passes into the common transverse tube c at the end, thence into the inclined compartment or passage in the header d or d^2 , into the transversely disposed tube c of a tube set on the opposite side of the column 85 or header and in another or higher plane, the hot fluid then returning in an opposite direction across the casing and thence into the transverse tube c at the opposite end of the tube set, thence through the adjacent 90 vertically disposed column or header d^1 or d^3 at the opposite end of the casing, passing thence into an oppositely disposed transverse tube c of another longitudinal tube set 95 disposed in the same plane as that last traversed, through which it again returns across the casing and so on, the hot fluid circulating as in a coil and passing through the whole circuit of connected tube sets b , c of 100 each nest.

It will be understood that the upper part of the headers d , d^2 form part of the nests 1 and 2 while the lower part of the headers d , d^2 form part of the nests 3 and 4 respectively, and that the headers d , d^2 are both 105 provided in their opposite parallel side walls with two vertical series of holes d^7 , d^8 , (Figure 5) for the reception of the transverse tubes c of the two vertical series provided as hereinbefore described. The headers d^1 and d^3 are, however, advantageously provided in two separate upper and lower parts as illustrated in Figures 3, 4 and 6, the respective parts being advantageously bolted or connected together at opposite 110 sides to form an integral column by means of bolts passing through the outwardly extending flanges i provided for the purpose. The upper parts of the headers d^1 and d^3 are provided with horizontal partitions h^1 (Figure 4) which form a vertical series of separate compartments or passages. In the respective oppositely disposed side walls of each of the headers d^1 and d^3 , two vertical 115 series of holes d^5 , d^6 (Figure 6) are provided for the reception of the respective transverse tubes c of the two vertical series provided as hereinbefore described. The arrangement of the holes d^5 , d^6 at each side 120 is such that they each open out into the 125

respective compartments formed by the horizontal partitions h^1 and each alternate hole on the same side is disposed on distinct vertical lines as is the case with the holes d^1 and d^2 , but the holes of the series d^3 , d^4 that open out into any one compartment are disposed on different vertical lines. Thus each transverse tube c on one side of the header d^1 or d^3 is disposed in position opposite to a blank part of the opposite side wall, while the hole provided for the reception of the transverse tube c at the opposite side is also oppositely disposed to a blank part of the wall. In the construction illustrated, the nests 1 and 2 are intended for the passage through them of the hot residue from the still. Thus each compartment formed by the partitions h^1 in the upper part of the header d^1 or d^3 serves for the conveyance of the hot residue from one transverse tube c on one side of the upper part of the header d^1 or d^3 to another transverse tube c out of vertical alignment with it on the other side.

25 The hot residue is admitted into the nest 1 or 2 through a branch of the residue main, connected with the inlet pipe fitting j which is connected to an elbow pipe fitting k mounted near the bottom of the upper part of the column or header d^1 or d^3 , whereby the hot residue passes into the lowermost compartment of the upper part of the header d^1 or d^3 thence into the transverse tube c of the evaporator tube set at the opposite side of the header, the residue then passing to the opposite header d^1 or d^3 and thence into one of the compartments therein formed by the inclined walls h as before described. The residue thus passes upwardly and successively through tube sets disposed at a higher level, the hot residue thus circulating to and fro along the tube sets and through the compartments in the respective headers, until it reaches the uppermost compartment of the header d^1 or d^3 whence it passes outwardly through the elbow fitting k^1 and through the residue outlet pipe fitting j^1 to return to the residue main.

50 The respective nests 3 and 4 disposed beneath the nests 1 and 2 are provided for the passage therethrough of hot vapour from the still and inasmuch as the hot vapour is substantially reduced in temperature and partially condensed in passing through these nests, it is necessary to provide means for draining the condensate as before described. The lower part of the headers d , d^2 form part of the nests 3 and 4 and are provided in the lower part as well as 55 in the upper part with inclined compartments or passages for the purpose described, but the lower separate parts of the headers d^1 , d^3 are provided with horizontal partitions h^2 of the form hereinafter described.

60 65 These partitions are, however, not integral-

ly formed in the lower part of the header d^1 or d^3 , but they are separately provided to extend across the cavity therein and of a shape corresponding thereto, and are provided near their peripheral edge h^3 with a recess within which asbestos or other suitable packing may be inserted to ensure a tight joint. The partitions h^2 are centrally provided with a downwardly depending tubular part h^4 adapted for reception within in a centrally disposed cup h^5 , an interval being allowed between the upper edge of the cup h^5 and the partition h^2 and between the lower end of the tubular part h^4 and the bottom of the cup h^5 , as well as between the bottom of the cup h^5 and the partition h^2 next beneath it, so that thus on the condensate from the evaporator tubes passing into the respective compartments in the lower end of the header d^1 or d^3 , it flows down the tubular part h^4 of the partition h^2 from one compartment into the cup h^5 disposed in that next beneath it. It will be understood that the condensate may then flow over the upper edge of the cup h^5 into that compartment and thence pass in the same way beneath the cup h^5 through the tubular part h^4 of the partition h^2 next beneath. Thus the condensate from the respective tube sets passes from compartment to compartment in the lower part of the header d^1 or d^3 and may discharge through the outlet pipe h^6 . (Figure 1.)

Advantageously the cups h^5 may be provided with upwardly and downwardly protruding parts or extensions serving as means by which the cups may be concentrically held around the downwardly protruding parts h^4 of the partitions, to rest upon the partitions beneath them and to support the partitions above them. Or instead the partitions h^2 may be provided with such extensions, or separate interposed distance pieces may be provided for the same purpose. These protruding parts may be so formed with recesses or interruptions as to maintain access for the liquid from the compartment to the tubular outlet part of the partition to permit the overflow into the compartment from the respective cups.

55 It will thus be understood that the draining of the respective tube sets and compartments of the headers is effected under conditions that ensure the circulation of the vapours and prevent a gas lock.

60 It will be also understood that the course of the hot vapour through the respective nests 3 and 4 is the same as the course of the hot residue through the nests 1 and 2, the vapour being admitted to the respective nests from branches of the respective vapour outlet pipe from the still, connected in each case to the inlet pipe fitting n connected to an elbow fitting n^1 mounted 65 near the bottom of the lower part of the

4
column or header d^1 or d^2 . The hot vapour circulates through the respective connected tube sets rising upwardly at each complete circuit, the proportion not condensed and 5 gas being discharged at the opposite end of the nest from the header d or d^2 through the elbow fitting n^2 whence it passes through the vapour outlet fitting n^3 and thence to the condenser.

10 The crude oil or other liquid to be pre-heated is sprayed or allowed to drip from a series of horizontally disposed spraying pipes t which surmount the respective nests 1 and 2. The spraying pipes t consist of 15 four longitudinal pipes of a length and distance apart corresponding to the evaporator tube sets and they are similarly connected at their respective ends to transverse pipes t^1 which are common to the two sets of 20 longitudinal spraying pipes t . The transverse pipes t^1 have a central outwardly extending branch which is connected to an inlet pipe fitting t^2 at the respective sides of the casing, so that thus the crude mineral 25 oil is admitted to the spraying pipes t from both sides of the casing and passes through the common transverse pipes t^1 to the respective sets of longitudinal spraying 30 pipes. The longitudinal spraying pipes t are provided at intervals with outlet holes t^3 which are uniformly spaced apart in line at the top of the pipes and similar holes may be provided in the transversely disposed pipes t^1 . Thus the crude oil flows 35 over the spraying pipes and uniformly drips on to the evaporator tubes disposed beneath them, falling to the bottom of the casing whence it drains off through sealed outlets, while the uncondensed vapour leaves 40 through an outlet fitting n^4 provided on the side wall of the casing.

45 Means are advantageously provided to ensure the uniform dripping of the crude oil upon the evaporator tubes. In the illustrated construction vertically disposed curtain plates t^4 are mounted in line immediately beneath the longitudinal spraying pipes t and these curtains are conveniently carried by means of symmetrical clamping plates t^5 which are clamped upon the longitudinal pipes t . The curtain plates t^4 are 50 advantageously provided in two or more parts as indicated and at their lower edges are serrated and, with a view to ensure the dripping of the oil in line immediately over the evaporator tubes of the uppermost set, their lower edges are conveniently tied to these evaporator tubes by means of wire as illustrated in Figures 1 and 3. Similar curtain plates t^4 may be provided between the nests where intervals occur between nest and nest as between the nests 2 and 4 (Figure 3).

55 It will be understood that the nests should be properly set to ensure the uniform drip-

ping of oil throughout the vertical series of evaporator tubes and that the spraying pipes should be set and maintained level. For this purpose the spraying pipes are supported at the middle of each transverse pipe t^1 upon the top of the respective headers d , d^1 , d^2 , d^3 , by means of an adjustable support t^6 mounted on the top of the respective headers and provided with a recess adapted for the reception of the junction of the transverse pipes t^1 and the outwardly extending inlet fitting t^2 , while at each end of each transverse pipe t^1 an angle plate t^7 is secured to the frame members e and adapted to carry an adjusting stud t^8 to bear upon the said pipe t^1 . There is thus an angle plate t^7 at each corner of each set of spraying pipes t so that thus any desired adjustment can be effected to maintain the connected sets of spraying pipes level.

70 It will be further understood that any other means for ensuring the uniform dripping of the crude oil over the evaporator tubes may be employed.

75 It will be understood that the casing a is not provided with any external lagging or heat non-conductor so that condensation of the vapours derived from the crude oil may be facilitated under suitable atmospheric conditions, but the casing may be partially lagged or a heat non-conductor provided in order to retard condensation in the casing, and similarly under any 80 conditions requiring it, cooling water may be caused to drip over the casing or any other known means employed for ensuring the required temperature conditions within the casing.

85 The bottom or any part of the casing 90 may be heat insulated. An inner cover plate or roof u may be mounted within the casing a and in position above the nests of evaporator tubes and above the spraying or dripping pipes. The inner cover plate 95 may be suitably suspended, as indicated, from the top plate of the casing and may have a slightly curved or arch form to permit of the condensed vapour from the crude oil dripping from it and flowing over its 100 edge near the side walls of the casing, and this inner cover plate may be formed from corrugated sheet metal. Furthermore the respective nests may be surrounded by inner metal side walls or plates v which may also be of a corrugated form. These metal side walls or plates v may be 105 suspended from the bars f of the frame and they may be carried from these bars by means of hook shaped lugs v^2 . The metal side walls or plates v may have spaces 110 provided between their adjacent vertical edges and between their upper edges and the inner cover plate u , so that they do not 115 completely enclose the space in which the 120 metal side walls or plates v may have spaces 125 provided between their adjacent vertical edges and between their upper edges and the inner cover plate u , so that they do not completely enclose the space in which the 130

nests are mounted. Furthermore the metal side walls or plates v are so provided that in positions beneath the inlet fittings of the spraying pipes for the crude oil and the residue and vapour inlet and outlet fittings, the upper edge of the wall or plate is diverged outwardly as at v^3 so that any liquid at the joints may drain into the bottom of the casing. On each wall of the 10 casing near the bottom, gutters w, w, w^1, w^2 , are provided for the reception of the condensed vapour from the inner cover plate u and from the side walls or plates v which are outwardly diverted for the purpose at 15 v^4 . The gutters are so disposed that the end of the gutter w^1 at one end is disposed above the level of the gutters w, w at the sides, and the gutter w^2 at the opposite end is disposed beneath the ends of the gutters 20 w, w so that thus the condensate may flow from gutter to gutter, the disposition or inclination of the respective gutters being such as to cause the flow of the condensate so that it passes to the lowermost point of 25 the gutter w^2 where a receptacle w^3 is provided, in which a liquid seal against the escape of vapours, is maintained, and whence the condensate may run off.

In the bottom the casing steam pipes x 30 are laid and these pipes may be provided at the top with a series of perforations. The branches of the steam pipes may extend immediately beneath each series of evaporator tube sets as illustrated in Figure 2 so that thus the crude oil may be 35 vaporized in the presence of steam, or any other suitable fluid medium for the same purpose.

The liquid residue may be supplied to 40 the respective heat exchangers when provided in vertical series through an upwardly extending main or supply pipe from which branches may extend to the inlet and outlet respectively of each nest, and controlling valves may be provided for controlling the amount of the residue admitted 45 to particular heat exchangers of the series, as described in the specification filed on the co-pending application first mentioned.

50 The respective inlet and outlet pipe fittings for the residue and vapour and crude oil may be adapted for ready disconnection by having their ends screwed within the corresponding fittings connected to the respective headers or to the spraying pipes v^1 so that thus when it is desired to remove the nests for cleaning or repair, it is only necessary to remove the packing from the glands, to disconnect the respective pipes 55 and to unscrew the inlet and outlet pipe fittings referred to, whereupon it is possible to withdraw the respective nests by removing the side plate a^1 and moving their frames along the rails provided for this 60 purpose. On the removal of the side plate 65

a^1 the condensate outlet pipe h^6 (Figure 1) is accessible for disconnection. The sides of the casing may be lined with baked clay tiles or the like to minimize chemical reaction.

70 It is obvious that the invention may be carried into effect by a different construction of elements necessary for carrying out the operations involved. The invention is thus not confined to the construction hereinbefore specifically described for it is possible for the respective nests comprising the circuit of tube sets to be otherwise constructed without departing from the invention.

75 I claim:

1. In a heat exchanger a nest of evaporator tubes comprising vertical series of evaporator tube sets that are horizontally disposed and so connected to vertical columns at opposite ends of the nest that the heat yielding fluid may circulate successively through evaporator tube sets on opposite sides of the nest as in a coil, substantially as described.

80 2. In a heat exchanger, a nest of evaporator tubes comprising vertical series of evaporator tube sets, each tube set comprising a number of parallel horizontally disposed tubes, vertical columns at the respective ends of the said nest with which the said evaporator tube sets are connected, and means within the said vertical columns successively to convey the heat yielding fluid 85 from the plane of one of the evaporator tube sets at one side of the columns to that of another evaporator tube set at the other side, substantially as described.

90 3. In a heat exchanger, a nest of evaporator tubes comprising vertical series of horizontally disposed evaporator tube sets, columns at each end of the nest to which the said evaporator tube sets are connected, means for successively conveying the heat yielding fluid from the plane of one of the 95 evaporator tube sets at one side of the columns to that of another evaporator tube set at the other side, and means for draining the said nest substantially as described.

100 4. In a heat exchanger, a nest of evaporator tubes comprising vertical series of horizontally disposed evaporator tube sets, columns at each end of the nest to which the said evaporator tube sets are connected, means for successively conveying the heat 105 yielding fluid from the plane of one of the evaporator tube sets at one side of the columns to that of another evaporator tube set at the other side, and means for draining the said nest comprising partitions in 110 one of the columns forming compartment therein by which a gas seal is formed by the condensate which flows downwardly 115 from one of the said compartments to the other, substantially as described.

5. A heat exchanger provided with nests of evaporator tubes, each nest comprising vertical series of evaporator tube sets, each tube set comprising a number of parallel 50 horizontally disposed tubes, vertical columns at the respective ends of each of said nests, means for conveying the heat yielding fluid from the plane of one of the evaporator tube sets at one side of the said columns to that of another evaporator tube set at the other side, and sprayer pipes disposed above the said evaporator tubes, said sprayer pipes being composed of a number of parallel tubes disposed in alignment with the tubes of the 60 evaporator tube sets, substantially as described.
6. A heat exchanger provided with nests of evaporator tubes, each nest comprising vertical series of evaporator tube sets, each 65 tube set comprising a number of parallel horizontally disposed tubes, vertical columns at the respective ends of each of said nests, means for conveying the heat yielding fluid from the plane of one of the evaporator tube sets at one side of the said columns to that of another evaporator tube set at the other side, sprayer pipes disposed above the said evaporator tubes, said sprayer pipes being composed of a number of parallel tubes disposed 70 in alignment with the tubes of the evaporator tube sets, and curtain plates by means of which the liquid to be sprayed is distributed as a film over the evaporator tubes, substantially as described.
7. A heat exchanger provided with nests of evaporator tubes, each nest comprising vertical series of evaporator tube sets, each tube set comprising a number of parallel 75 horizontally disposed tubes, vertical columns at the respective ends of each of said nests, means for conveying the heat yielding fluid from the plane of one of the evaporator tube sets at one side of the said columns to that of another evaporator tube set at the other side, sprayer pipes disposed above the said evaporator tubes, said sprayer pipes being composed of a number of parallel tubes disposed 80 in alignment with the tubes of the evaporator tube sets, and curtain plates by means of which the liquid to be sprayed is distributed as a film over the evaporator tubes, substantially as described.
8. A heat exchanger provided with nests of evaporator tubes, each nest comprising vertical series of evaporator tube sets formed of horizontal and parallel tubes, 85 columns to which the said evaporator tube sets are respectively connected at their ends, means by which the heat yielding fluid is successively conveyed from one of the evaporator tube sets at the one side of the columns to that of another evaporator tube set on the other side, and means by which the nests are adapted for use of both the hot residue from the still as well as the hot 90 vapour, substantially as described.
9. A heat exchanger provided with nests of evaporator tubes comprising vertical series of evaporator tube sets, an outer casing within which the said nests are mounted, inner plates or walls within the said casing and enclosing the said nests, and means for the reception of the condensate from the 95 said inner plates or walls, substantially as described.
10. A heat exchanger provided with nests of evaporator tubes comprising vertical series of evaporator tube sets mounted between vertical columns, a casing within which the nests are mounted, removable frames upon which the said nests are carried, rails mounted in the bottom of the said casing and beneath the said removable frames beneath and at the respective sides of the nest and in position transversely with respect to the evaporator tube sets therein, wheels by which the removable frames are capable of being supported and moved on 100 the said rails, inlet and outlet pipe fittings disposed laterally on the said casing adjacent the headers of the respective nests, and means for the disconnection of the said fittings from without.

PERCY MATHER.
